US0D1015366S

(12) **United States Design Patent** (10) **Patent No.:** **US D1,015,366 S**
Hayter et al. (45) **Date of Patent:** **** Feb. 20, 2024**

(54) **DISPLAY SCREEN OR PORTION THEREOF WITH GRAPHICAL USER INTERFACE**

(71) Applicant: **ABBOTT DIABETES CARE INC.**, Alameda, CA (US)

(72) Inventors: **Gary A. Hayter**, Oakland, CA (US); **Timothy C. Dunn**, San Francisco, CA (US); **Yashesvini V. Ram**, Newark, CA (US); **Claire A. Cunningham**, Point Richmond, CA (US); **Justin N. Williams**, Oakland, CA (US); **William Koo Lee**, Alameda, CA (US)

(73) Assignee: **ABBOTT DIABETES CARE INC.**, Alameda, CA (US)

(**) Term: **15 Years**

(21) Appl. No.: **29/845,954**

(22) Filed: **Jul. 12, 2022**

Related U.S. Application Data

(63) Continuation of application No. 29/766,528, filed on Jan. 15, 2021, now Pat. No. Des. 957,438, which is a continuation of application No. 16/942,414, filed on Jul. 29, 2020, now abandoned.

(57) **CLAIM**

The ornamental design for a display screen or portion thereof with graphical user interface, as shown and described.

DESCRIPTION

The FIGURE is a front view of a display screen or portion thereof with graphical user interface showing our new design.

The outer perimeter illustrated by dashed broken lines in the FIGURE illustrates a display screen or portion thereof and forms no part of the claimed design. The remaining broken lines in the FIGURE form part of the claimed design.

1 Claim, 1 Drawing Sheet
